KEY RING

Olof V. Anderson, Cowesett, R. I.

Application November 8, 1944, Serial No. 562,497

5 Claims. (Cl. 70—459)

1

The present invention relates to the jewelry art, and has particular reference to a novel construction for a key ring.

The principal object of the invention is to provide a novel key ring which may be manually locked to prevent accidental loss or removal of keys therefrom.

Another object of the invention is to provide a key ring of the type having a spring pressed key retaining closure, with a positive lock device.

Still another object of the invention is to provide a novel key ring made of a small number of readily manufactured and easily assembled parts.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Fig. 1 is a plan view of the key ring construction embodying the novel invention;

Fig. 2 is a side view thereof;

Fig. 3 is a plan view of the hollow top therefor;

Fig. 4 is a plan view of the key retained element and the cooperating closure element;

Fig. 5 is a perspective view of the closure element spring;

Fig. 6 is a perspective view of the movable lock element;

Fig. 7 is a sectional detail showing the arrangement of the parts when the key ring is in locked position; and

Fig. 8 is a view similar to Fig. 7, the key ring parts being shown in position for permitting insertion or removal of a key.

It has been found desirable to provide a key ring of the type having a movable spring jaw, with a manually operable device which can be shifted to positively lock the movable jaw in place, whereby loss or detachment of keys from the key ring is prevented. To this end, I have provided a movable lock element which may be manually shifted to positively lock the movable jaw in key retaining position, and which may be manually shifted to permit the movable jaw to open for the insertion or the removal of a key from the key ring.

Referring to the drawing, which illustrates a preferred embodiment of the invention, the novel key ring 10 includes a hollow top 11, which may be stamped out of sheet metal or may be made of bakelite or other suitable material, and a key retainer 12 which is preferably formed as an

2

L-shaped wire having one end 13 secured within the hollow top 11 and having the other end 14 extending upwardly towards and terminating below the hollow top 11. A movable closure element 15 cooperates with the key retainer 12, and is pivotally mounted in the hollow top 11 by means of a pivot pin 16 seated in aligned openings 17 in the side walls of the hollow top 11, whereby the upper end 18 of the closure member 15 is positioned within the hollow top 11 and the lower end 19 of the closure member extends downwardly and is adapted to move into aligned contact with the key receiving end 14 of the key retainer.

A coil spring 20, shaped as shown in Fig. 5, has one end 21 provided with a finger 22 which seats within a vertical slot 23 in the upper end 18 of the movable closure member, the other end 24 of the spring being bent slightly to normally rest against the roof of the hollow top 11, as shown in Fig. 7. With the parts assembled as shown in Fig. 7, the closure member is spring pressed so as to always urge its lower end 19 into aligned contact with the key receiving end 14 of the key retainer; when the lower end 19 is pressed inwardly for the purpose of inserting or removing a key, the closure member assumes the position shown in Fig. 8, with the spring 20 compressed as illustrated and exerting a resilient pressure on the movable closure member to urge it back to closing position.

The above described construction permits the insertion or removal of a key by movement of the closure member against the tension of the spring 20; and it is preferred to provide a positive lock against accidental and unintentional movement of the closure member. To secure this advantageous result, a lock element 25, see Fig. 6, is mounted for sliding movement along the base of the hollow top 11, and consists of a plate 26 and two parallel sides 27 and 28, the sides serving as supports for a resilient cross rod 29. The movable lock element 25 is preferably made of ornamental metal, and the front side 27 may be ornamented in any desired manner. The sides 27 and 28 are normally positioned on the exterior of the hollow top 11, and the cross rod 29 extends transversely through the hollow top 11 in suitable aligned slots 30 in the sides thereof, whereby the movable lock element may be laterally shifted, as hereinafter described.

Referring now to Fig. 4, the upper end 18 of the closure element is provided with a notch 31, the end of the movable element being preferably beveled, the notch 31 being adapted to releasably receive the cross rod 29 of the movable lock ele-

ment 25 when the movable lock element is shifted laterally as shown in Fig. 7. In this position the cross rod 29 firmly seats within the notch 31, and maintains its position because of its resilience to prevent movement of the upper end 18 of the movable closure member, thus positively maintaining the lower end of the closure member in contacting alignment with the key receiving end 14 of the key retainer. A lateral shift of the movable lock element as illustrated in Fig. 8 removes the cross rod 29 from the notch 31 and permits opening movement of the closure member. The cross rod 29 thus functions as a catch element which cooperates with the notch 31 as a catch element, for obtaining a releasable lock, the improved construction providing a positive lock key ring.

While I have described a specific constructional embodiment of my invention, it is obvious that changes in the size, the positioning, and the arrangement of the parts, and use of other materials than those specified above, may be made to suit the requirements for different key ring designs, without departing from the spirit or scope of the invention as defined in the appended claims.

I claim:

1. In a key ring, a hollow top, a key retainer comprising a wire element having one end secured in the top and the other end extending upwardly and towards the top, a cooperating closure element pivotally mounted in the top and having a portion extending towards the key receiving end of the wire element, a spring device normally urging said closure element into aligned contact with said key receiving end and yieldingly resisting turning movement of the closure element, whereby to permit insertion of a key over said key receiving end, and a latch device comprising a U-shaped frame, and a cross rod in said frame extending through aligned slots in the sides of the top, said closure element having a notch for releasably holding the frame cross rod.

2. In a key ring, a hollow top open at the bottom, an L-shaped wire element having its upper portion secured in one end of the hollow top and extending downwardly, transversely and then upwardly towards the other end of the hollow top, a second wire element pivotally mounted in the other end of the hollow top and having one portion positioned in the hollow top and a second portion extending downwardly from the hollow top to seat on the upwardly extending portion of the L-shaped wire element, spring means in said hollow top engaging the portion of the second wire element in the hollow top to urge the second portion into seating position, the portion of the second wire element in the hollow top having a latch notch, and a manually movable lock device slidably mounted in the hollow top and having a catch element movable into and out of said latch notch.

3. In a key ring, a hollow top open at the bottom, an L-shaped wire element having its upper portion secured in one end of the hollow top and extending downwardly, transversely and then upwardly towards the other end of the hollow

5 top, a second wire element pivotally mounted in the other end of the hollow top and having one portion positioned in the hollow top and a second portion extending downwardly from the hollow top to seat on the upwardly extending portion of the L-shaped wire element, spring means in said hollow top engaging the portion of the second wire element in the hollow top to urge the second portion into seating position, the portion of the second wire element in the hollow top having a beveled end and a latch notch, and a manually movable lock device slidably mounted in the hollow top and having a resilient cross bar movable over said beveled end and into and out of said latch notch.

4. In a key ring, a hollow top open at the bottom, an L-shaped wire element having its upper portion fixedly secured in one end of the hollow top and extending downwardly, transversely and then upwardly towards the other end of the hollow top and terminating below said hollow top other end, a second wire element pivotally mounted in the other end of the hollow top and having an inner portion positioned in the hollow top and an outer portion extending downwardly from the hollow top to seat on the upwardly extending portion of the L-shaped wire element, and a coil spring positioned in said hollow top adjacent the pivotal mounting of the second wire element, said coil spring having one extended end secured to the inner portion of said second wire element positioned in the hollow top, and its other end also extended and engaging the roof of the hollow top.

5. In a key ring, a hollow top open at the bottom, an L-shaped wire element having its upper portion fixedly secured in one end of the hollow top and extending downwardly, transversely and then upwardly towards the other end of the hollow top and terminating below said hollow top other end, a second wire element pivotally mounted in the other end of the hollow top and having an inner portion positioned in the hollow top and an outer portion extending downwardly from the hollow top to seat on the upwardly extending portion of the L-shaped wire element, and a coil spring positioned in said hollow top adjacent the pivotal mounting of the second wire element, the inner portion of said second wire element positioned in the hollow top having a retaining slot therethrough, said coil spring having one extended end bent to seat into said slot and its other end also extended and engaging the roof of the hollow top.

OLOF V. ANDERSON.
